Glass Manufacturing Company, Inc., New York, N.Y., a corporation of New York

Filed Apr. 18, 1961, Ser. No. 64,808

Term of patent 14 years

(Cl. D58—5)

The characteristic feature of my design resides in the combination on the bottle disclosed of the depressed hand grip on one of the sides, as shown in full lines on the drawing; which grip is decorated substantially as shown.

I claim:

The ornamental design for a bottle, substantially as shown and described.
